EMIL GUNTHER AND FRED J. GUNTHER, OF RACINE, WISCONSIN.

MACHINE FOR CUTTING UP STRING BEANS.

Application filed May 17, 1924. Serial No. 713,989.

To all whom it may concern:

Be it known that we, EMIL GUNTHER and FRED J. GUNTHER, citizens of the United States of America, residing at Racine, Wisconsin, have invented certain new and useful Improvements in Machines for Cutting Up String Beans, of which the following is a specification.

Our invention relates to a machine for cutting up string beans into short lengths. It comprises the combination of a mass-distributor, by which term we mean to describe an instrumentality which receives a large quantity of string beans, say a peck 10 or two, in a promiscuous mass-form at one end and feeds them out and distributes them in appropriately small quantities, preferably in a continuous stream, at the other end to another element which we call a carrier-straightener, which term we use to describe an instrumentality by which the beans, which have been fed to it in small but unarranged quantities are, during their carriage, arranged in parallel directions or 20 straightened, this carriage or transport in the meanwhile taking the beans to a radially shelved wheel.

Now this wheel has mounted on its axis a series of radial shelves and these shelves 30 are slotted, at equal intervals, in planes at right angles both to the shelves and to the axis of the wheel. As a consequence, we can mount upon a stationary knife-head a series of knives at intervals equal to those 35 by which the slots are separated and thereby have the knives register with the slots and penetrate up to the point where the shelves become part of the solid structure of the wheel axis. Therefore, all the beans 40 which lie upon a given shelf will, as the rotary shelf moves by the stationary knives, be cut into appropriate lengths and the bean pieces will be subsequently discharged from the shelf as the shelf which carries 45 them tilts down.

Such combination of the mass-distributor, a carrier-straightener, a radially-shelved and slotted wheel and a cutter-head with spaced knives constituting a string bean 50 cutter, we believe to be new.

Again, in this general combination, we have found particularly useful a mass-distributor which consists of a rotary conical

or cylindrical hopper having an opening at one end into which the mass of beans is fed, just as the beans come from a bushel basket, and in which hopper is arranged a helical blade which breaks up this large mass into small groups or even into a steady stream. Such mass-distributor is peculiarly 55 efficient in our combination because it handles the beans in a way which is very practical in the actual operation and because it cooperates with peculiar efficiency with the form of carrier-straightener which 60 we employ.

The carrier-straightener, in fact, consists of an upper and a lower shelf and a pair of endless sprocket chains at each edge, which chains are carried on two pairs of 70 sprocket wheels and are connected by equally spaced transverse slats running along the shelves, the parts being arranged so that the string beans fall onto the upper shelf, along which these slats travel, the 75 beans being first carried away from the shelved wheel by the pressure of the transverse slats against them, which pressure acts to straighten the beans and to put them into positions parallel to each other and 80 transverse to the carrier, the beans now fall from the end of the upper shelf and land on the top of the lower shelf, along which they are pushed by these same transverse slats toward the shelved wheel and 85 the knives. It is to be particularly noted that the slats are so timed as to operate in synchronism with the shelves of the wheel so as to deposit the straightened beans, which now lie parallel with the axis of the 90 wheel, onto that shelf of the wheel which is in time with the corresponding slat. In this way the machine is not unduly increased in length, in fact its length is reduced nearly one-half, and the hopper finds 95 place above the carrier-straightener so as to make a compact structure.

The more detailed feature of novelty will be pointed out in the claims.

Referring now to the drawings:

Figure 1, is a vertical longitudinal section of the machine.

Figure 2, is a horizontal section of the machine looking down on line 2—2 of Figure 1.

Figure 3, is a perspective view partly 105 broken away, of the entire machine,

Figure 4, is a detailed perspective view showing the inside of the feed hopper.

Figure 5 is a perspective view looking from the side of the machine opposite to 5 that of Figure 3.

Figure 6, is a detailed sectional view thru the knives on line 6-6 of Figure 5.

Figure 7, is a detailed sectional view of the radially shelved wheel.

10 Figure 8, is a transverse sectional view on line 8-8 of Figure 7.

Figure 9, illustrates one of the knives, and

15 Figure 10, illustrates the spaces between the knives.

The mass-distributor "A" consists of a center cylindrical portion 1, having a conical end 2, into which the mass of beans are fed, and an end 3 from which they are discharged in a distributed fashion. Within 20 the mass-distributor there is provided a helical flange 4 which breaks up the mass of beans in the body of the distributor into a small regularly flowing stream which is 25 discharged thru the mouth 5.

Means are provided for supporting and 30 rotating the mass-distributor or hopper. These means may be varied. As illustrated, the mouth 5 is connected to a shaft 6 by means of a spoke 7, the inner end of the spoke being secured to the shaft and the outer end to the mouth by means of a strap 8. The shaft is rotated by bevel gears 9, 10, the gear 9 being carried by a counter- 35 shaft 11 carrying a sprocket 12 at one end. The sprocket 12 is driven from the power shaft 13 of the machine, the power shaft being provided with and driving fast and loose pulleys 14 on the other side of the 40 machine. The pinion 13' meshes with pinion 15, carried by shaft 16 and a chain 17 passes around sprockets 18, 12. By these means counter-shaft 11 is driven from the power shaft 13, thus driving bevel gears 9, 10 and 45 rotating the shaft 6 to which the mass-distributor "A" is secured. The mass-distributor is thus slowly rotated. The gears 9 and 10 are carried in a protecting casing 20.

Means are provided for tilting the mass- 50 distributor so as to regulate the gravity feed of the beans and their rate of discharge from the distributor. In the form of the invention illustrated, a pair of standards 21 are provided having slots 22 at the top. Arms 23 swing on shaft 11 and are cross-connected by means of a collar 24, the latter surrounding shaft 6. By raising and lowering the arms and securing them in 55 their raised and lowered position by bolts 25, passing thru slots 22, the shaft 6 can be vertically adjusted and with it the mass-distributor "A," about the shaft 11.

60 The beans are discharged from the tilting discharge mouth 5, onto the stationary upper platform of the straightener. While

discharging the beans are carried more or less to one side. Means are provided for guiding the beans as they drop from the distributor so that they are spread more evenly across the platform. Fingers, or 70 baffle bars, 26, 27 are fastened to the side wall 28 toward which the beans are discharged, the finger 26 being shorter than the finger 27. As the beans drop down over the fingers they are spread more evenly over 75 the platform. The side walls 28 are connected at the back by wall 29, so as to prevent the beans from being discharged too far forward.

75 The carrier-straightener 30, upon the upper shelf 31 of which the beans are discharged from the hopper "A", consists of the short upper shelf 31 and a lower longer shelf 32. At opposite ends of the shelves are shafts 13, 33, which each carry a pair 80 of sprocket wheels 34, around which passes a pair of endless sprocket chains 35, which are connected by slats 36 uniformly spaced apart. These slats slide over the shelves and push along any string beans which may 85 have landed on the upper shelf from the mass-distributor "A", and in being pushed along to the right in Figure 1 they are gradually straightened. When the beans on the upper or short shelf get to the end of that 90 shelf, they are dropped down on the lower shelf, practically retaining their parallelism in falling, whereupon the slats push them toward the left in Figure 1 and still further 95 straighten them.

100 Any beans which, in falling from the upper to the lower shelf, have risen at an angle above the lower shelf, are pushed down to lie flat on this lower shelf by the cross bar 37. The right hand sprocket 105 wheel shaft in Figure 1 is adjusted to tighten the sprocket chains by having its bearings working in slides which are controlled by adjusting screws 38 in a manner which is well understood and is illustrated 110 in Figure 1. The inset plate 39 in Figure 3, which is matched by a similar plate on the opposite side of the machine shown in Figure 5, supports the two shelves 31 and 32.

115 We now describe the radially shelved wheel 40 which consists of disk-sections 41 having radial spokes 42 which, by means of key slots 43, are strung upon the power shaft. There are spacing devices 44 between the disks 41 and the disks are clamped 120 together by sleeves 45, which are held in clamping position by screws 46. The various spokes 42 of adjacent disks align so as to constitute radial shelves, upon which the aligned beans are pushed by the cross-slats 36 of the carrier-straightener, the movement of the slats and of the radial shelves 125 being timed as before explained.

130 But as will be evident, these shelves have in them a number of slots in planes perpen-

icular both to the shelves and to the wheel axis, the slots running crosswise to the shelves. Into these slots fit the knives.

A cross bar 47 with a cutting edge will 5 shear any beans that may ride the shelves on their outside edges, one part of the bean dropping into one pocket between the shelves and the other into the adjacent pocket.

- 10 The knives 48 for cutting up the beans are mounted on a pivoted rod 49 about which they can swing slightly, the amount of the swing being determined by the slotted portions 50 of the knives thru which slotted 15 portions bolts 51 pass. The knives are separated by spacing blocks 52. The knives thus project into the slots between the shelves, and can yield slightly in cutting.

The entire knife frame is mounted so as 20 to be capable of being thrown clear from hard substances such as sticks, as the shelves turn. The knife frame is carried by end plates 53, one at each side, the end plates having angular portions 54 thru which pass 25 bolts 56, pulled by springs 57. A rocking movement of the knife frame is thus permitted with relation to the seats supporting the angular portions 54.

30 Springs 58 are secured to the end plates 53 of the knife frame and yieldingly hold the knife frame in place.

A delivery chute 60 receives the cut up 35 portions of the beans and discharges them from the machine. This chute may be swung vertically and kept in its adjusted position by bolt 61 passing thru swinging arm 62.

Having thus described the construction, the operation will be clear, the beans are 40 poured into the mass-distributor and when the machine is driven, they are cut up by the knives and discharged from the machine in cut up pieces, by the delivery chute. It will be understood that changes may be made in 45 the construction of the machine without departing from the principle of the invention.

What we claim is:

1. A string-bean cutter comprising the 50 combination of a mass-distributor, a carrier-straightener, a rotary wheel with slotted shelves and knives passing within the slots, substantially as described.

2. A string-bean cutter comprising the 55 combination of a mass-distributing hopper having a helical blade therewithin, a carrier-straightener, a wheel with slotted shelves and knives passing within the shelves, substantially as described.

3. A string-bean cutter comprising the 60 combination of a mass-distributor, a carrier straightener consisting of an upper and lower shelf and transverse slats operating along the shelves, a wheel with radial and slotted shelves onto which the slats deposit the beans

and knives passing within the slots to cut the beans into pieces, substantially as described. 65

4. A string-bean cutter comprising the combination of a carrier-straightener, consisting of an upper and a lower shelf, sprocket chains running along the edges of the shelves and transverse slats connecting the chains, a rotary wheel with radial and slotted shelves timed to work in synchronism with the slats which deposit the beans thereon; and knives passing within the slots to 70 cut the beans into pieces, substantially as described. 75

5. A string bean cutter comprising the combination of two pairs of sprocket wheels 80 spaced apart an upper and a lower shelf, the upper shelf being shorter than the space between the sprocket wheels, two sprocket chains mounted on the pairs of sprocket wheels and moving lengthwise of the shelf, transverse slats connecting the sprocket chains, a rotary wheel with radial and slotted shelves timed to work in synchronism with the slats which deposit the beans thereon, and knives passing within the slots to 85 cut the beans into pieces, substantially as described. 90

6. A string-bean cutter comprising the combination of a carrier-straightener having transverse slats actuated by chains to 95 straighten the beans, moving in one direction at the top and in the other direction at the bottom of their travel, thereby diminishing the length of the device, a rotary wheel with radial and slotted shelves timed to work in synchronism with the slats which deposit the beans thereon and knives passing within the slots to cut the beans into pieces, substantially as described. 100

7. A string-bean cutter comprising the combination of a mass-distributor, a carrier-straightener consisting of an upper and a lower shelf and transverse slats operating along the shelves, a finger between the mouth of the hopper and the upper shelf, a wheel with radial and slotted shelves onto which the slats deposit the beans and knives passing within the slots to cut the beans into pieces, substantially as described. 105 110

8. A string-bean cutter comprising the combination of a mass-distributor, a carrier-straightener consisting of an upper and a lower shelf and transverse slats operating along the shelves, a pair of fingers of unequal length between the mouth of the hopper and the upper shelf over which the beans fall, a wheel with radial and slotted shelves onto which the slats deposit the beans and knives passing within the slots to cut the beans into pieces, substantially as described. 115 120

9. A string-bean cutter comprising the combination of a rotary, mass-distributing hopper, means for adjusting the inclination of said hopper, a carrier-straightener, a 125

wheel with slotted shelves and knives passing within the slots, substantially as described.

19. A string-bean cutter comprising the combination of a rotary, mass-distributing hopper, a shaft connected to said hopper for rotating it, a collar thru which said shaft passes, means for vertically adjusting said collar so as to vary the inclination of the 10 hopper, a carrier-straightener, a wheel with slotted shelves and knives passing within the slots substantially as described.

11. A string-bean cutter comprising the combination of a rotary, mass-distributing hopper, a shaft to which the hopper is secured for rotating it, a carrier-straightener consisting of an upper and a lower shelf, sprocket chains running along the edges of the shelves and transverse slats connecting 20 the chains, a power shaft for driving said chains, a rotary wheel with radial and slotted shelves, gearing between said power shaft and wheel, thereby timing the wheel to work in synchronism with the slats, bevel 25 gears for driving the hopper shaft, sprocket wheels and a chain for driving the bevel gears from the radially shelved wheel shaft, and knives passing within the slots of the shelves to cut the beans into pieces.

30 12. A string-bean cutter comprising the combination of a mass-distributor, a carrier-straightener consisting of an upper and a

lower shelf, transverse slats operating along the shelves, a wheel with radial and slotted shelves onto which the slats deposit the 35 beans, a cross bar extending over said wheel and knives passing within the slots to cut the beans into pieces, substantially as described.

13. A string-bean cutter comprising the 40 combination of a mass-distributor, a carrier-straightener consisting of an upper and a lower shelf, transverse slats operating along the shelves, a cross bar extending across and above the lower shelf between which bar and 45 the shelf the beans pass, a wheel with radial and slotted shelves onto which the slats deposit the beans and knives passing within the slots to cut the beans into pieces, substantially as described.

14. A string-bean cutter comprising a feeding straightener for the beans, a wheel with radial and slotted shelves onto which the beans are deposited, a cross bar extending over said wheel and cooperating therewith for shearing the beans that ride the shelves on their outside edges, and knives 55 passing within the slots to cut the beans into pieces, substantially as described.

In testimony whereof, we have signed our 60 names to this specification.

EMIL GUNTHER.
FRED J. GUNTHER.
